US0D1011717S

(12) **United States Design Patent** (10) Patent No.: **US D1,011,717 S**
(45) Date of Patent: ** Jan. 23, 2024

- (54) **SHOE**
(71) Applicant: **PUMA SE**, Herzogenaurach (DE)
(72) Inventor: **Jason Raleigh**, Beverly, MA (US)
(73) Assignee: **PUMA SE**, Herzogenaurach (DE)
(**) Term: **15 Years**
(21) Appl. No.: **29/891,912**
(22) Filed: **May 11, 2023**

Related U.S. Application Data

- (63) Continuation-in-part of application No. 29/740,212, filed on Jul. 1, 2020, now Pat. No. Des. 992,258.

(57) **CLAIM**

The ornamental design for a shoe, as shown and described.

DESCRIPTION

FIG. 1 is a top, right, front perspective view of an ornamental design for a shoe;

FIG. 2 is a left side elevational view of the shoe of FIG. 1; and,

FIG. 3 is a right side elevational view of the shoe of FIG. 1. The dash-dash lines are included for the purpose of illustrating portions of the shoe that form no part of the claimed design. The dash-dot-dash lines are included for the purpose of illustrating boundary lines that form no part of the claimed design.
